United States Patent

Des. 237,763
Patented Nov. 25, 1975

237,763

UPHOLSTERED CHAIR

Henry James, Pontiac, Ill., assignor to Pontiac Furniture
Industries, Inc., Pontiac, Ill.

Filed Nov. 8, 1972, Ser. No. 304,848

Term of patent 14 years

Int. Cl. D6—01

U.S. Cl. D6—31

FIG. 1

FIG. 3

FIG. 2

FIG. 1 is a front quarter perspective view of an upholstered chair in accordance with my design;

FIG. 2 is a side elevational view of the same; and

FIG. 3 is a plan view.

The back side, which is not illustrated, is substantially flat and plain.

I claim:

The ornamental design for an upholstered chair, substantially as shown and described.
